UNITED STATES PATENT OFFICE

2,452,731

HOTBOX COOLER

Sam W. Clutton, Missoula, Mont.

Application March 8, 1946, Serial No. 652,952

5 Claims. (Cl. 184—1)

1

This invention relates to a device for lubricating an overheated journal box, known as a "hot box," and it is one object to provide a device which may be mounted upon a journal box of a railroad car axle or other rotary shaft and serve as a carrier for a reserve supply of oil which will be discharged into the journal box in case the journal box becomes overheated and thus prevent the journal box from developing a "hot box" and catching fire.

Another object of the invention is to provide a lubricant holder so constructed that the lubricant will be normally held in a reservoir which is sealed by plugs formed of fusible material so that in case the journal box becomes overheated the plugs will melt and allow the reserve supply of lubricant to flow into the journal box.

Another object of the invention is to provide a device of this character so constructed that when the fusible plugs melt oil in the reservoir of the device may flow through a tube having outlet spouts spaced from each other longitudinally of the device and thus discharged into the journal box in such manner that all parts of the journal box will be quickly lubricated and prevented from catching fire.

Another object of the invention is to provide the device with an auxiliary reservoir containing a substance which is normally held in the auxiliary reservoir by fusible plugs and will be released when the journal box becomes overheated so that trainmen or other workmen will be warned that the journal box has become overheated due to improper lubrication and needs attention.

Another object of the invention is to provide a device of this character which is simple in construction and very compact and may be readily applied to journal boxes of conventional size and construction.

The invention is illustrated in the accompanying drawings wherein:

Figure 1 is a sectional view taken longitudinally through the improved journal box lubricator and signal.

Figure 2 is a sectional view taken along line 2—2 of Figure 1.

Figure 3 is a section taken along line 3—3 of Figure 1.

Figure 4 is a perspective view of the oil reservoir of the device.

Figure 5 is a perspective view of the drum into which oil flows from the oil reservoir.

Figure 6 is a perspective view of the distributor pipe.

2

Figure 7 is a perspective view of the reservoir for holding odor-producing material.

Figure 8 is a perspective view of a perforated disk constituting a vent plate.

Figure 9 is a perspective view of a plug for closing an end of the cylindrical body of the device.

This lubricant holder and signal has a cylindrical body 1 which is formed of strong metal and has its ends internally threaded to receive plugs 2, each plug being formed with a socket 3 to receive a wrench by means of which it is screwed into the body or removed therefrom. Vent holes 4 are formed through each plug at the inner end of its socket 3. From the under portion of the body project necks 5 and 6 which have their lower portions tapered so that they will have wedging fit in the sockets 7 at upper ends of ports 8 and are firmly secured by welding, as shown at 9, or in any desired manner. The ports 8 are formed through the upper portion of the journal box 10 and when oil is discharged into the ports 8 it enters the journal box at points spaced longitudinally thereof and onto the axle or shaft at such points that the axle 11 will be quickly supplied with oil.

Within the casing or body 1 is a cylindrical container 12 formed of sheet metal and constituting an oil reservoir and between opposite ends of the reservoir and the heads or plugs 2 are a smaller container 13 and a drum 14 which are also formed of sheet metal and between the oil reservoir and the drum and the container are rubber spacers 15 and 16, the spacer 15 being formed with a center opening 17. A rubber spacer 18 having a center opening 19 is disposed between the drum and the adjacent plug 2 and between this plug and the spacer 18 is a metal plate 20 formed in its central portion with vent openings 21. Since the openings 21 of the vent plate 20 are between the openings 4 of the plug and the opening 19 of the spacer 18 air may enter the drum, through the vent opening 14a and causes oil to flow freely from the drum. The reservoir 12 is formed along its under portion with a longitudinally extending channel 22 which is aligned with channel 23 formed along the under portion of the drum and in these channels is mounted a discharge pipe 24 having branches 25 and 26 which fit into the bores of the necks 5 and 6. From an inspection of Figure 1 it will be seen that oil flowing from the reservoir 12 into the drum 14 will enter the pipe 24 through the entrance 27 at the inner end thereof and then flow through the pipe and out through its branches to the ports 8 through which it enters the journal box. At one end the reservoir 12 is formed with outlet openings 28 closed by plugs

29 of fusible metal and when the journal box becomes overheated, due to lack of proper lubrication, the heat entering the drum will melt the fusible plugs and oil in the reservoir will flow through the opening 17 of the spacer and through the opening 14^b of the drum and into the drum from which it will flow through the pipe 24 and its branches to the journal box. A cup 30 carried by the drum and resting upon a tongue 31 projecting from the adjoining end of the oil reservoir is provided to catch the melted plugs 29 and prevent them from passing out of the drum with the oil and into the journal box.

When a journal box becomes overheated and the reserve supply of oil is delivered to it, it is desired to warn the train crew of the fact that a journal box needs attention. Therefore the container or auxiliary reservoir 13 is filled with an odorous substance which may be gas or other suitable material. This substance is confined in the container 13 by fusible plugs 32 which tightly close the outlet openings 33 and when heat from an overheated journal box melts the plugs 29 it will also melt plugs 32 and allow escape of the odorous material through the openings 33 and the openings 4 of the adjoining closure 2 of the casing 1. As soon as the odor of the material escaping from reservoir 13 is noticed the train crew will repack and lubricate the journal box and, after removing the empty containers 12 and 13 insert new ones.

Having thus described the invention what is claimed is:

1. A device of the character described, comprising a casing open at its ends, removable closures for ends of said casing, necks extending from said casing for establishing communication, between the casing and a journal box; a container in said casing constituting a reservoir for an auxiliary supply of oil; a drum in said casing between the reservoir and one end of the casing; the reservoir and said drum having under portions formed with aligned channels; a discharge pipe extending longitudinally in said channels and having branches entering the necks, said pipe having its inner end communicating with the drum; said reservoir having openings in one end for delivering oil to the reservoir normally closed by plugs meltalbe to release oil in response to predetermined heat of the journal box, a receptacle for catching melted plugs dislodged from outlets of the reservoir, the drum and the adjoining closure for an end of the casing being formed with air inlet openings, an auxiliary reservoir in said casing at the opposite end of the oil reservoir for holding an odorous material, the adjoining closure for an end of the casing being formed with outlet openings, and plugs for closing the openings of the auxiliary reservoir formed of fusible metal adapted to be melted and dislodged to release the odorous material when the journal box becomes overheated.

2. A device of the character described comprising a horizontal casing having removable closures for its ends, necks extending downwardly from said casing and adapted to be secured in openings formed in a journal box, an oil reservoir in said casing, a drum in the casing between the reservoir and one end of the casing, the end of the reservoir

confronting said drum being formed with an outlet closed by a plug of fusible metal, a discharge pipe extending from said drum along the reservoir and having branches entering the necks for delivering oil to the journal box when the plug is melted in response to predetermined temperatures of an overheated journal box, the drum and the closure for the adjoining end of the casing being formed with air inlet openings, and an auxiliary reservoir for an odorous material disposed in the casing at the opposite end of the oil reservoir from said drum and normally closed by a plug of fusible metal.

3. A device of the character described, comprising a casing having removable closures for its ends, means for mounting the casing upon a journal box, an oil reservoir in said casing having an outlet at one end normally closed by a fusible plug, a drum in said casing for receiving oil from the reservoir when the plug is melted in response to overheating of the journal box, means in said drum for holding the dislodged plug, a pipe extending from said drum and outwardly of the casing for delivering oil to an overheated journal box, an auxiliary reservoir in said casing for holding odorous material, said auxiliary reservoir having an outlet closed by a fusible plug adapted to be dislodged when melted in response to heat of an overheated journal box.

4. A device of the character described comprising a casing having removable closures for its ends, means for mounting the casing upon a journal box, an oil reservoir in said casing having an outlet at one end normally closed by a fusible plug, a drum in said casing for receiving oil from the reservoir when the plug is melted in response to overheating of the journal box, a pipe leading from said reservoir and outwardly of the casing for delivering oil to an overheated journal box, said drum having an air inlet, and an auxiliary reservoir for holding odorous material having an outlet closed by a plug of fusible material adapted to be melted and dislodged when the journal box becomes overheated.

5. A device of the character described comprising a casing having removable closures for its ends, means for mounting the casing upon a journal box, an oil reservoir in said casing having an outlet at one end normally closed by a fusible plug, a drum in said casing for receiving oil from the reservoir when the plug is melted in response to overheating of the journal box and a pipe leading from said reservoir for delivering oil to an overheated journal box.
